United States Patent Office

HENRY E. POND, OF FRANKLIN, MASSACHUSETTS, ASSIGNOR TO HIMSELF
AND AMOS P. WOODWARD, OF THE SAME PLACE.

Letters Patent No. 67,672, dated August 13, 1867.

RECEPTACLE FOR HARNESS.

The Schedule referred to in these Letters Patent and making part of the same.

TO ALL TO WHOM THESE PRESENTS SHALL COME:

Be it known that I, HENRY E. POND, of Franklin, in the county of Norfolk, and State of Massachusetts, have invented a new and useful Receptacle for Harnesses; and do hereby declare the following to be a full, clear, and exact description of the same, reference being had to the accompanying drawings, making part of this specification, in which—

Figure 1 is a front elevation,

Figure 2 a side elevation, and

Figure 3 a vertical and longitudinal section of my invention.

The object of this invention is to provide a ready means of enclosing and preserving an animal's harness where it is not convenient or practicable to construct or maintain a room especially for the purpose, as well as to protect such harness from the effects of air and dust, and keep it in a moist state, or one highly favorable to the preservation as well as appearance of it.

The invention consists of a rectangular frame with metallic corners, and with a wooden back, such frame being covered with cloth, having a paint or composition applied to its outer surface, and with the interior body of such cloth saturated with a non-drying oil or compound, a door being applied to front of the frame, and being also covered with cloth prepared as above.

In the drawings above referred to A A denote two frames, rectangular in shape, and made of wood, and united at their four corners by strips, B B, of metal, thus forming an upright box or closet. The front frame A is rebated for reception of the door C, which is also composed of a rectangular frame, c, and is hinged to the frame A in the usual manner. Both the frame A A and door C are covered with cloth, or an equivalent material, such cloth having a water-proof or other composition or coating applied to its outer surface, and with its interior surface or body saturated with oil, as before described. The back D is composed in the present instance of wood, and has an extension at top, in which an eye, d, is formed for hanging the closet in any convenient position. The interior surface of the back is also provided with hooks, e e e, &c., for the reception of the various portions of the harness.

A wardrobe constructed as above described is portable, and can be transported or moved about with ease. The harness contained in it is kept in a moist state, and free from dust and dirt, greatly enhancing its wearing qualities as well as to preserve it and improve its appearance. The oil with which the cloth is saturated contributes greatly to this effect. The frames A A may be made of metal or wire if preferable to wood.

I claim, as a new article of manufacture, a receptacle for harness and other like articles, in which a wooden or other suitable skeleton-frame, A, is combined with a water-proof covering, the body of which is saturated with a non-drying oil or compound, as herein set forth.

HENRY E. POND. [L. S.]
